UNITED STATES PATENT OFFICE.

PERCIVAL F. KING, OF VANCOUVER, BRITISH COLUMBIA, CANADA.

HOSPITAL-MATTRESS.

1,341,564.

Specification of Letters Patent. Patented May 25, 1920.

Application filed August 22, 1918. Serial No. 250,980.

To all whom it may concern:

Be it known that I, PERCIVAL F. KING, a citizen of the Dominion of Canada, residing at Vancouver, in the Province of British Columbia, Canada, have invented certain new and useful Improvements in Hospital-Mattresses, of which the following is a specification.

This invention relates to a sanitary hospital or invalid's bed, of that class wherein provision is made for draining any liquid or other excreta through the mattress into any suitable receptacle beneath, when it is undesirable that the patient be moved.

The invention is particularly described in the following specification, reference being made to the drawings by which it is accompanied, in which:

Figure 1 is a vertical section through a central portion of a mattress showing the application of the device thereto.

Fig. 2 is a plan of the same with the cover pad of heat non-conducting material removed showing the drainage plate.

Fig. 3 is a similar view of an alternative form of plate, and

Fig. 4 is a section on the line 4—4 in Fig. 2.

The device comprises a pan 2, preferably of thin sheet metal, converging from a circular or oval beaded upper edge 3 toward a central tubular delivery 4.

This pan 2 is inserted in a recessed aperture 5 prepared for it in the mattress 6 and the upper edge 2 is drawn below the general upper surface of the mattress by flexible connections 7, preferably of chain links, which connections pass through the body of the mattress and are removably connected by pins 8 to a washer plate 9 apertured to pass over the lower end of the tubular delivery 4 and bear against the underside of the mattress 6.

The diminished elasticity of the mattress, where the pan is applied, is supplemented by a coil spring 10 between the underside of the pan 2 and the washer plate 9.

Within the beaded upper edge 3 of the

pan is fitted a drainage plate 11, the entire surface of which is apertured, as shown in Fig. 3, or, as shown in Fig. 2, it has a central aperture 12 and drainage grooves 13 radiating thereto, which grooves will impart a certain measure of strength to the plate to withstand flexure.

As previously stated, the upper beaded edge 3 of the pan is drawn down into a recess provided for it below the general surface of the upper side of the mattress 6, and in this recess is placed an apertured pad 5 of cork or other suitable material.

Although the tubular delivery aperture 4 is shown of relatively large size as fitting the device for use as a bed pan when the cork pad 5 and drainage plate 11 are removed, there are many cases where this requirement is unnecessary and where consequently the tubular delivery may be small.

If the material of the pad 5 is of sufficient strength to sustain the weight imposed upon it the drainage plate as a detached part may be dispensed with.

Having now particularly described my invention, I hereby declare that what I claim as new and desire to be protected in by Letters Patent, is:

In combination with a mattress, a funnel-shaped pan having a central discharge outlet removably secured within a correspondingly shaped aperture in the mattress, a washer plate, flexible connections between the upper edge of the pan and the washer plate, said connections passing through the mattress body, the upper edge of the pan being recessed beneath the general upper surface of the mattress, a drainage plate in the upper end of the pan located in a plane beneath the adjacent surface plane of the mattress, and a perforated plate of heat non-conducting material resting on the drainage plate, the exposed surface of said perforated plate substantially coinciding with the adjacent face of the mattress, substantially as shown and described.

In testimony whereof I affix my signature.

PERCIVAL F. KING.
